CLAIM

The ornamental design for a magnet flexible stand, as shown and described.

DESCRIPTION

FIG. 1 is a front, right and top perspective view of a magnet flexible stand, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the magnet flexible stand wherein a cellphone is magnetically attached thereto.

The cellphone shown in broken lines in the drawings is included for the purpose of illustrating the magnet flexible stand in use and forms no part of the claimed design.
